UNITED STATES PATENT OFFICE.

JOHN J. TATUM, OF BALTIMORE, MARYLAND, ASSIGNEE, BY MESNE ASSIGNMENTS, TO
P. H. MURPHY COMPANY, OF PARNASSUS, PENNSYLVANIA, A CORPORATION OF
PENNSYLVANIA.

CAR.

1,240,622.

Specification of Letters Patent. Patented Sept. 18, 1917.

Application filed May 22, 1912. Serial No. 693,953.

To all whom it may concern:

Be it known that I, JOHN J. TATUM, a citizen of the United States, residing at Baltimore, in the State of Maryland, have invented certain new and useful Improvements in Cars, of which the following is a specification.

The objects of my invention are, first, to combine the fascia and eaves flashing in one integral member; second, to provide a strip running longitudinally of the car secured to the side plate under the fascia, whereby the side sheathing of the car may be removed for repairs without removing or disturbing the flashing or fascia; third, to provide the inner edge of the flashing with an upward return bend terminating in an under rebent portion and to provide the outer edges of the roof sheets with an under rebent terminating in an under return bend, whereby a loose joint is formed between the roof sheets and the flashing, along a line short of the eaves of the car; and with these and minor objects in view, my invention consists of the 25 parts and combination of parts as will be hereinafter more fully pointed out.

In the drawings,

Figure 1 is a perspective view of a car, broken away, embodying my invention;

Fig. 2 is an enlarged detail sectional view; and

Fig. 3 is a detail perspective view of the combined fascia and flashing. Fig. 4 is a detail sectional view.

The reference numeral 1 represents the side plate of a car, 2 a side post, 3 a carline, 4 the roof substructure, and 5 the side sheathing.

While I have selected the type of car shown in the drawing for the purpose of illustrating my invention, it will be understood that the use of my invention is not restricted to this type.

One of the most frequent repairs to a freight car is the replacing of side sheathing which has been damaged or torn away by "side wiping." In making such a repair, it is necessary to remove the fascia and flashing inasmuch as they overlie the top ends of the sheathing and in removing these, they are frequently materially damaged, especially the fascia.

I overcome these objections by securing the strip 6 to the side plate 1, said strip extending longitudinally the length of the

car. The top ends of the side sheathing fit snugly against the under face of said strip, while the fascia or a flashing extends below the joint between the sheathing and said strip to prevent water entering said joint, although the flashing and fascia are not secured to the side sheathing, thus the side sheathing, which is nailed at its upper ends to the side plate below the said strip, may be removed without disturbing the fascia or flashing, which will result in a material reduction in the cost of repairing side sheathing.

The reference numeral 7 represents a metallic flashing formed with a bead 11 which acts as a water shed or drip to discharge water clear of the side sheathing. The flashing 8 is formed integrally with the fascia and extends over the eaves onto the car roof and is upwardly rebent at its inner edge as at 9 along a line back from the eaves, said rebend 9 being spaced from the body of the flashing. The edge of the rebend 9 is rebent under as at 10 and spaced from the rebend 9, as shown in the drawing.

The roof sheets 12 are connected together at their side edges by any of the well known loose joints, such for instance as shown in the Murphy patents to permit of relative movement between them transverse of the car, while the outer ends of the roof sheets are rebent under along a line short of the eaves of the car as at 13 and spaced from the body of the sheet, the edge of the bend 13 being also rebent under as at 14 and spaced from the rebend 13 as shown. A are hood castings such as the Murphy hood caps, as shown in the W. P. Murphy Patent No. 1,115,090, for example.

The combined fascia and flashing having been secured to the strip 6 by means of the nails 15, the rebent outer edges 13 of the roof sheets 12 are interlocked with the return bend 9 of the flashing forming therewith a loose joint which permits movement of the sheets longitudinally of the car.

The flashing is provided with bosses 16 throughout its length on which the underbent edge 13 of the roof sheets rests, whereby the weight of the outer edge of the sheet 12 is sustained and the underbent edge 13 of the roof sheet is spaced from the rebend 9 of the flashing so as to reduce wear between the bends 9 and 13 to a minimum and at the same time space the bends 9 and 13 apart to

prevent moisture from creeping from one to the other.

The purpose of the rebends 10 and 14 on the roof sheets and flashing respectively, is 5 to serve as sheds or drips for moisture. For instance, water striking the under face of the bent portion 13 of the roof sheet will strike against the shed or drip 14 and be deflected onto the flashing; it cannot "creep" 10 around the edge of the bend 13. The same is true of the shed or drip 10 of the flashing, thus there is no danger of moisture in any form beating under the roof sheets past the joint between the roof sheets and flashing. 15 The bosses 16 are represented as being hemispherical, inasmuch as this form offers the least obstruction to water, snow, etc., thus preventing the accumulation of water, snow and ice between the flashing and the 20 bend 13 of the roofing sheets, besides presenting a reduced bearing for the bend 13 of the sheets, thereby reducing friction and wear on the bend 13 when the roof sheets move longitudinally and transversely relatively to the car incident to the movements 25 of the car in transit.

By forming the flashing and fascia from one piece of sheet metal, I am enabled to dispense with the usual wooden fascia, thus 30 not only materially reducing the original cost of the car, but reducing the weight of the car, as the metal fascia is much lighter than the usual oak fascia. Any reduction in the weight of a freight car which does 35 not weaken the car is considered material by the railroads.

In Fig. 4, I have shown the fascia formed without a bead at its top.

I claim:

40 1. In a car roof the combination with roof sheets thereof terminating short of the eaves, of an integral metal fascia and flashing strip, secured along the eaves of the car and lapping the upper ends of the 45 sheathing and having its flashing portion disposed on top of the car and loosely engaging the eaves ends of the roofing sheets, said strip overhanging and secured to the side of the car and having a lengthwise extending rib projecting outwardly and 50 spaced therefrom to constitute a fascia.

2. In a car roof, the combination with roof sheets having an under return bend at their outer ends, of a flashing, said flashing 55 having a portion thereof so placed and reinforced as to constitute a fascia, being constructed to extend on top of the car and terminating in an upward return bend adapted to engage the under return bend 60 of the roof sheets and form therewith a loose joint.

3. In a car roof, the combination with roof sheets having an under return bend at their outer ends, of a combined fascia and 65 flashing extending on top of the roof and

terminating in an upward return bend at its inner end constructed to engage the under return bend of the roof sheets and form therewith a loose joint, and spaced bosses on the upper face of the flashing within its 70 return bend on which the return bend of the roof sheet rests.

4. A combined fascia and flashing for car roofs terminating in an upward return bend and having bosses on the upper face of its 75 body portion positioned under said return bend.

5. In a car roof, the combination with roof sheets and an integral metal fascia and flashing strip loosely engaging said sheets, 80 of a strip extending longitudinally of the car and secured to the side plate, side sheathing secured to the plate with the upper end thereof positioned under said strip, said flashing being anchored to the strip and 85 covering the joint between the strip and sheathing.

6. In a car, the combination with the side plate, of a strip of the same thickness as the side sheathing secured thereto and extending longitudinally of the car, and a metal fascia secured to said strip and extending below the bottom of said strip, whereby a recess is formed between said 90 extended portion of the fascia and the side plate and a reinforcing rib in said extending portion.

7. In a car, the combination with the side plate, of a strip of the same thickness as the side sheathing secured thereto and 100 extending longitudinally of the car, and a metal fascia secured to said side strip and extending downward below the plane of the bottom face of the strip, whereby a recess is formed between said extended portion 105 and the side plate and a reinforcing rib in said extending portion, and side sheathing secured to said side plate with its upper end in said recess.

8. In a car roof, the combination with 110 roof sheets terminating adjacent to the eaves, of an integral metal fascia and flashing secured along the eaves of the car and having its flashing portion arranged upon the top of the car and its fascia portion 115 overhanging the side of the car, said flashing portion extending under the eaves end of the roof sheets and said fascia portion being provided with a lengthwise extending rib projecting from the side of the car. 120

9. In a car roof, in combination with roof sheets having their eaves ends loosely held on the car, an angle shaped metal flashing and fascia strip arranged lengthwise along the side and top of the car at the eaves and 125 lapping under the ends of said roof sheets, side sheathing for the car, the upper ends of the side sheathing terminating below the eaves of the car, said flashing strip being rigidly secured to the side of the car 130

above said side sheathing and having its lower marginal portion stiffened lengthwise by a hollow rib and spaced away from the side of the car, the lower edge of said flashing strip lapping over the upper ends of said side sheathing.

10. In a car, the combination with a roof substructure and side walls, of an integral metal fascia and flashing strip extending longitudinally along the eaves of the car, the flashing portion extending inwardly on top of the roof substructure, and the fascia portion having an offset portion extending along the upper portion of the side wall and outwardly beyond the latter and the roof.
15. In a car roof, the combination with

roof sheets having their eaves ends loosely held on the car, an angle shaped metal flashing and fascia strip arranged lengthwise along the side and top of the car at the 20 eaves and lapping under the ends of said roof sheets, said flashing strip being rigidly secured along the side of the car and having a lengthwise extending guard portion projecting outwardly therefrom.

25. In testimony whereof I affix my signature in presence of two witnesses.

JOHN J. TATUM.
